PLURAL COMPARTMENT REFRIGERATING APPARATUS

Lawrence A. Philipp, Detroit, Mich., assignor to Nash-Kelvinator Corporation, Detroit, Mich., a corporation of Maryland

Application February 19, 1953, Serial No. 337,825

2 Claims. (Cl. 62—117.25)

This invention relates to refrigerating apparatus and 15 more particularly to food freezer units.

One of the objects of the invention is to provide an improved arrangement of the components of a home food freezer unit to decrease cost and facilitate assembly of such units.

More specifically it is an object of my invention to form a pair of cabinet liners such that a space therebetween is made available to a machinery compartment for a refrigerant condensing unit, and to enclose the liners and machinery compartment within a single casing.

Another object of the invention is to provide an improved double compartment home food freezer of economical construction and high operating efficiency by providing two similar liners of single compartment freezers arranged with their machinery compartment offsets in opposed relationship and in such manner as to increase heat insulation between the storage compartments and between the compartments and the machinery compartment.

Further objects and advantages of the present invention will be apparent from the following description, reference being had to the accompanying drawings, wherein a preferred form of the present invention is clearly shown.

In the drawings:

Fig. 1 is a plan view of my home freezer unit having parts broken away and in section;

Fig. 2 is a front view of the home freezer unit having parts broken away and in section; and

Fig. 3 is a diagrammatical illustration of the refrigerating system of the home freezer unit.

Referring to the drawing by characters of reference, the numeral 20 designates, in general, a large size freezer cabinet having a pair of laterally spaced food storage compartments 22. The compartments 22 have access openings in the top of the cabinet which are closed by lids 24 that may be hinged to the cabinet rear wall.

In order to construct economically a large freezer unit of the size indicated, I provide a pair of cabinet liners 26 having offset ends arranged in opposed relation to provide a space therebetween for a refrigerant condensing unit 28, and I enclose the liners and condensing unit by a one piece casing 30. The liners 26 are box-shaped and the offsets in the opposed end walls of each has a horizontal portion 32 and a vertical portion 34.

The liners 26 form the inner wall surfaces of the storage compartments 22 and are cooled to a low freezing temperature by a refrigerant evaporator coil 36. Preferably the coil 36 is arranged in good heat conducting relation with the liners and extends along the side, ends and offset walls thereof.

Below the horizontal walls 32 and between the vertical walls 34 of the liner offsets, I provide a housing 38 which forms a machinery compartment for the refrigerant condensing unit 28. The housing 38 may be made of sheet metal and may extend from front to rear of the cabinet. Between the casing 30, liners 26, and the machinery

2

compartment housing 38, heat insulation 40 is provided to decrease seepage of heat into the food storage compartments 22. With respect to the insulation 40, I space the liners 26 a distance apart such that each of the opposed upper end walls thereof, as at 42, has about the same thickness of insulation that is provided in conventional single liner units, or the same thickness of insulation as used between the liners 26 and casing 30 at the outer end and at the side walls thereof. As a result, I obtain the advantage of having substantially twice the thickness of insulation between the liners 26 and between the liner walls 42 and the condensing unit 28, thereby assuring that there will be no appreciable heat transfer between the liners or between the condensing element and the liners.

As shown in Fig. 3, the refrigerant condensing unit comprises in general, a refrigerant motor-compressor unit 44 and a refrigerant condenser 46. A conduit 48 connects the motor-compressor unit to the condenser 46 and the condenser supplies liquid refrigerant to the evaporator 36 by means of a capillary tube 50. A refrigerant accumulator 52 is connected by the usual return conduit 54 to the motor-compressor unit 44. Preferably, a fan 56 is provided to cool the condenser 46 and is arranged to discharge air from the machinery compartment through an opening (not shown) in the cabinet front wall.

The cabinet is reinforced by a pair of access opening frames 60 for compartments 22 and connect the liners 26 to the casing 30 to increase rigidity of the structure. The liners 26 have outturned flanges 62 around the upper edges thereof which may be secured to the frames 60 by screws or by other suitable means. A tie plate 64 which is secured to the casing 30 spans and connects the frames 60 together and thus also ties the liners 26 together to increase rigidity of the structure.

From the foregoing description, it will be understood that I have provided an improved construction and arrangement of the components of food freezers to construct large size units economically. It will also be understood that by arranging two liners having opposed offset walls that a machinery compartment is provided within the confines of the casing for housing the condensing unit of the refrigerating system. In addition, it will be seen that by spacing the liners apart a distance such that each of the opposed, offset end walls has the established insulation thickness for single liner freezers that there is a substantially double wall thickness of insulation between the liners and between the liners and condensing element to insure against any appreciable transfer of heat therebetween.

Although preferred and modified forms have been illustrated, and described in detail, it will be apparent to those skilled in the art that various other modifications may be made therein without departing from the spirit of the invention or from the scope of the appended claims.

I claim:

1. Refrigerating apparatus comprising, a pair of box-like liners having end walls with lower oppositely directed offsets and the liners being in opposed spaced relationship, said offsets providing a space for a machinery compartment, a refrigerant condensing unit in said machinery compartment, refrigerant evaporator means on said liners operatively connected to said condensing element, a casing enclosing both of said liners, said liners having their outer end walls and side walls spaced from corresponding end and side walls of said casing, insulation between said corresponding end and side walls of said liners and casing to decrease seepage of heat from the ambient to the cabinet liners, said liners being spaced apart such that the distance between the opposed offset end walls above the offsets is substantially twice that of

the distance between the corresponding end and side walls of said liner and casing to prevent any appreciable exchange of heat between said liners, insulation between the opposed end walls of said liners above the offsets forming a partition between and common to said compartments, and a pair of laterally positioned hinged lids forming the top walls respectively of said compartments and resting on the upper edge of said common partition.

2. Refrigerating apparatus comprising, a pair of box-like liners arranged with end walls in opposed spaced relation, said opposed end walls having similar oppositely directed offset lower portions, a refrigerant condensing element housing between said offset portions of said liners, a casing enclosing said liners and said housing, said liners having outer end walls and opposite side walls spaced from corresponding end and side walls of said casing, insulation in the spaces between said corresponding end and side walls of said liners and casing, said

opposed end walls being spaced apart a distance substantially twice the spacing of said corresponding end and side walls of said liners and casing and said lower offset wall portions being each spaced from said housing substantially twice the distance of the space between said corresponding end and side walls of said liners and said casing, and heat insulation in the spaces between the opposed end walls of said liners above said offset and in the spaces between the offset wall portions and said housing.
